UNITED STATES PATENT OFFICE

EGBERT ALEXANDER, OF SAN FRANCISCO, AND CHARLES S. DUTTON AND GEORGE H. DERRICK, OF OAKLAND, CALIFORNIA; VICTORY A. DERRICK EXECUTRIX OF SAID GEORGE H. DERRICK, DECEASED, ASSIGNORS, BY MESNE ASSIGNMENTS, TO INSTOGRAPH, LTD., A CORPORATION OF CALIFORNIA

STAMPING DEVICE

Application filed August 17, 1926. Serial No. 129,870.

The present invention relates to improvements in stamping devices and has particular reference to a stamping device in which a plurality of printing wheels are used and are operated by a clock mechanism so as to expose on their active faces the time of the day and the date. The particular object of the present invention is to combine with a clock operated stamping device of this character, 5 an additional feature which allows the time elapsed between two stamping operations to be recorded on the object printed on. It is further proposed in the present invention to arrange the means for recording elapsed time 10 in such a manner that any number of operators may use the stamping device without interfering with the records of the other operators.

Other objects and advantages of our invention will appear as the specification proceeds.

The preferred form of our invention is illustrated in the accompanying drawing in which—

25 Figure 1 shows a vertical section through our device taken along line 1—1 of Figure 2,

Figure 2 a front elevation,

Figure 3 a horizontal section taken along line 3—3 of Figure 1,

30 Figure 4 a vertical section taken along line 4—4 of Figure 3, and

Figure 5 a vertical section taken along line 5—5 of Figure 3.

While we have shown only the preferred 35 form of the invention it should be understood that various changes or modifications may be made within the scope of the claims here-to attached without departing from the spirit of the invention.

40 A shaft 1 which receives rotary motion through the wheel 2 from any suitable clock mechanism in such a manner that the shaft makes one revolution per hour, its movement being divided into sixty impulses representing the sixty minutes of the hour, is suitably supported in a vertical frame comprising a plurality of vertical plates 3, 4, and 6.

A wheel 7, known as the minute wheel, is 45 fixed to the shaft by any suitable means as by flattening a section of the shaft as shown

at 8, and a second wheel 9 serving as hour wheel is loose on the shaft and is operated by the minute wheel in the manner illustrated in detail in Figure 4. As appears from this figure, a cam 11 projects from the outer face of the wheel 7 and allows one end 12 of an elbow 13 to ride thereon, the other end of the elbow being pivotally supported on a shaft 14 resting in the frame members 3 and 4. At the bend of the elbow a pin 16 extends 55 laterally and has pivoted thereto a pawl 17 the free end of which engages with a ratchet 18 fixed to the outer face of the hour wheel 9. The bent portion of the elbow is pulled forward by a spring 19.

It will be seen from this construction that during one revolution of the minute wheel 7, the free end 12 of the elbow rises on the cam 11 and thereby pushes back the bend of the elbow over the resistance of the spring 19, 60 allowing the pawl 17 to take a new bite. When the free end 12 of the elbow drops off the cam, the spring 19 pulls the elbow forward and causes the pawl 17 to advance the ratchet 18 and the hour wheel 9 fixed thereto 65 by the length of one tooth. The ratchet wheel 18 has 24 teeth so that there is one complete revolution of the hour wheel 9 during a day. A second pawl 21 engages with the ratchet 18 under pressure of the spring 22 to prevent 70 return movement of the ratchet.

A third wheel 23 is fixed to the free face of the ratchet 18 so as to partake of its rotary motion. This third wheel has the symbols AM and PM embossed thereon to correspond with two sets of figures 1 to 12 on the hour wheel 9. Three further wheels 24, 26, and 27 are supported on a small stub shaft 28, the wheel 24 exposing on its face a number of years such as 1926, 1927, 1928, etc., the second wheel 26 exposing figures running from 1 to 31 and representing the days of the month, and the third wheel 27 showing the 12 months of the year. Motion is transmitted from the hour wheel to the day wheel 26 in the manner illustrated in Figure 5 by a lever 29 pivoted to the frame as at 31 and provided with a tooth 32 riding on a cam 33 fixed to the face of the AM and PM wheel. The lever 29 is lifted by the cam so as to allow a pawl 34 80

85

90

95

100

to take a new bite on the ratchet 36 fixed relative to the day wheel 26 and when the tooth 32 drops off the cam a spring 37 pressing the lever 29 downwardly advances the 5 ratchet 36 by the length of one tooth, a second pawl 38 preventing return movement.

The principal feature of the present invention is the two wheels 41 and 42 both revolvably mounted on the shaft 1. These two 10 wheels, which may be called the lapsed time wheels, are used to indicate on the object printed, the time elapsed between two printing operations. They are arranged in such a manner that at the first operation they will 15 make a zero mark on the ticket and on the second operation they will mark the time elapsed between the two operations. When a workman enters a factory at 8:15 o'clock and introduces his time card into the device 20 to be printed, it will receive for instance, the following data:—

April 17 1926 AM 8 15 —

the two dashes standing for zero. If he 25 leaves at 11:30 o'clock his ticket will be printed as follows:—

April 17 1926 AM 11 30 3 15

indicating that he has been in the factory 30 three hours and fifteen minutes.

The two lapsed time wheels 41 and 42 are operated by means of two operating elements 43 and 44 in the following manner:

Above the shaft 1 there are supported in 35 the frame of the structure two shafts 46 and 47 which latter shaft carries at its front end the operating member 43 and at its rear end a gear wheel 48 transmitting motion through a gear wheel 49 on the shaft 46 to the gear 40 wheel 51 fixed to the lapsed time wheel 42. The second operating element 44 is fixed on the sleeve 53 revolvable on the shaft 47 which latter sleeve transmits motion to the lapsed time wheel 41 through a gear wheel 54 at the 45 rear end thereof, a second gear wheel 56 on the shaft 46 and a third gear wheel 57 fixed to the face of the lapsed time wheel 41. It will be seen that in this manner the two lapsed time wheels 41 and 42 may be turned 50 in any manner desired by manipulation of the two operating members 43 and 44.

The latter operating members move over 55 the two dials 58 and 59 respectively. These two dials are revolvably mounted on two concentric sleeves 61 and 62, and are operated by the hour and minute wheels 9 and 7, the dial 59 through the gear 64 on the rear end of the sleeve 62, the gear 66 on the shaft 46 and the gear 67 fixed to the hour wheel 9, while the dial 58 is operated through the gear 68, two pinions 69 and 71 transmitting its motion to a co-axial gear 72 mounted on a short shaft 73 aligned with the shaft 47, the 60 gear 74 on the shaft 46, and the gear 76 fixed 65

on the shaft 1 so as to move with the minute wheel 7.

The two dials 58 and 59 are geared to the hour and minute wheels 9 and 7 in such a manner that when the hour and minute 70 wheels 9 and 7 expose the correct time at their active printing faces the two dials expose the same time opposite a stationary point marked 77. The two lapsed time 75 wheels 41 and 42 are geared to their operating elements 43 and 44 respectively in such a manner that when the two operating elements are set opposite the stationary point 77, the two lapsed time wheels indicate two dashes at the printing face. The dials 59 80 and 58 are provided with a circular series of holes 78 and 79, the hour dial 59 having twenty four of these perforations corresponding to the hours of the day and the minute dial 58 having sixty of these perforations corresponding to the minutes of the hour. The operating elements 43 and 44 have pins 81 85 and 82 extending through the ends thereof, which pins may be inserted in the perforations 78 and 79 respectively so as to cause 90 the operating elements to revolve with the dials.

The device is used as follows:—

Assuming the operator enters the factory 95 at 8:15, he will find that the hour and minute wheels 9 and 7 disclose at the bottom, the numerals 8 and 15 respectively, while the 100 wheels 23, 24, 26 and 27 give the remaining data, namely, AM and the date. He will also find that the two dials 58 and 59 occupy such a position as to show opposite the stationary point 77 the correct time, namely 8 on the hour dial and 15 on the minute dial. The two operating members or hands 43 and 44 he may find in any position according to 105 their last use. The only operation required of him before stamping his time card, is to revolve the two hands 43 and 44 so that both are opposite the stationary point 77 which means that the lapsed time wheels 41 and 42 110 occupy a position so as to disclose zero or rather, two dashes at the bottom face. When 115 stamping his time card, the latter will receive the following data:—

April 17 1926 AM 8 15 —

The operator now goes on with his work 120 while other operators may use the device in the same manner, securing their respective 125 stamps on their cards.

When the first operator leaves the factory 130 at 11:30, he will find the following situation:

The hour and minute wheels 9 and 7 have advanced to show the correct time, namely, 11:30 at the bottom faces, while the two dials 125 58 and 59 have also advanced to show 11:30 opposite the point 77. The two hands 43 and 44 may be in any position left by the last operator. The first operator now proceeds 130 to place the two hands 43 and 44 in their

original positions, that is, at 8:15 on the dial, which means that the hands have been moved from a place opposite the stationary point 77 by an angle indicating a lapse of time of three hours and fifteen minutes and since the 5 lapsed time wheels 41 and 42 are geared to the hands 43 and 44 they move through the same angle and show at their bottom faces the lapsed time, namely, three hours and fifteen minutes, so that the stamp on the time 10 card will read:—

April 17 1926 AM 11 30 3 15

It will be seen that the device may be operated 15 successively by any number of users without any interference whatever.

We claim:—

1. In a stamping device of the character described, two parallel shafts, two printing 20 wheels mounted on one of the shafts, a sleeve on the second shaft in driving relation with one of the printing wheels, a second sleeve on the first sleeve in driving relation with the other printing wheel, a graduated dial 25 mounted on said second sleeve, and a hand on the second shaft, movable over the dial.

2. In a stamping device of the character described, two parallel shafts, two printing 30 wheels mounted on one of the shafts, a sleeve on the second shaft in driving relation with one of the printing wheels, a second sleeve on the first sleeve in driving relation with the other printing wheel, a graduated dial mounted on said second sleeve; a hand on the 35 second shaft movable over the dial, and a second hand on the first sleeve movable over the dial.

3. In a stamping device, a printing wheel, 40 a revolvable dial having graduations thereon corresponding to the characters on the printing wheel so as to indicate opposite a fixed point the character exposed on the printing wheel; a second printing wheel, a hand coaxially mounted with the dial and 45 being movable over the dial face; and an operative connection between the hand and the second printing wheels so as to cause the second printing wheel to print a character indicating the amount of rotation necessary to 50 revolve the first printing wheel to the position corresponding to a graduation opposite to the fixed point from a position corresponding to another graduation on the dial, when the handle is moved opposite said second graduation.

4. In a stamping device, a printing wheel, 55 a revolvable dial having graduations thereon corresponding to the characters on the printing wheel so as to indicate opposite a fixed point the character exposed on the printing wheel; a second printing wheel, a hand coaxially mounted with the dial and being movable over the dial face; an operative connection between the hand and the 60 second printing wheel so as to cause the sec-

ond printing wheel to print a character indicating the amount of rotation necessary to revolve the first printing wheel to the position corresponding to a graduation opposite to the fixed point from a position corresponding to another graduation on the dial, when the handle is moved opposite said second graduation; and means for allowing the hand to be fixed to the dial so as to bring about the change of position in the second 75 printing wheel automatically.

5. In a stamping device, a printing wheel, a datum marker, means bearing numerical indicia adapted successively to register with said datum marker, and means movable relative to said datum marker and to said first means for setting said printing wheel, said movable means being adapted to set said printing wheel in zero position when said movable means is in registry with said datum marker and with a selected one of said numerical indicia and being adapted to set said printing wheel in position to print the numerical difference between said selected numerical indicium and a second selected one of said numerical indicia when said second selected numerical indicium is in registry with said datum marker and said movable means is in registry with said first selected numerical indicium.

6. In a stamping device, a printing wheel, a datum marker, a disc bearing a plurality of numerals mounted to rotate past said marker, and a hand for setting said printing wheel to point the numerical difference between one of said numerals in registry with said datum marker and another of said numerals in registry with said hand.

7. In a stamping device, a mutable printing means, a datum marker, a member having numerical graduations, said member being movable relative to said datum marker for placing any selected one of said graduations in registry with said datum marker, and a setting member movable into registry with any selected one of said graduations for mutating said printing means to print the numerical difference between the graduation in registry with said datum marker and the graduation in registry with said setting member.

8. In a stamping device, a datum marker, a mutable printing means, a member displaceable with respect to said datum marker, a connection between said member and said printing means for mutating said printing means in proportion to the displacement of said member from said datum marker, and a member having graduations for indicating the displacement between said first member and said datum marker.

9. In a stamping device, a datum marker, a graduated disc rotatable with respect to said marker, means for rotating said disc at a constant rate, a printing wheel, and means

adapted to be optionally positioned to register with said datum marker or to register with one of the graduations on said disc for setting said printing wheel.

- 5 10. In a stamping device, a stationary datum marker, a graduated disc rotatable with respect to said marker, time means for rotating said disc, a printing wheel, and means rotatable with respect to said datum marker for setting said printing wheel.
- 10 11. A stamping device having a frame, a graduated disc supported by the frame, spaced apart rotatable shafts journaled in the frame, one of said shafts passing concentrically through the disc, an operating arm affixed to the last named shaft, two lapsed time wheels journaled on the other of the shafts, the first named shaft being geared to one of the lapsed time wheels, a sleeve carried by the first named shaft, an arm for rotating the sleeve, the other of the lapsed time wheels being geared to the sleeve and means for securing the arms against rotation with relation to the disc.
- 15 12. A stamping device having a frame, a graduated disc supported by the frame, spaced apart rotatable shafts journaled in the frame, one of said shafts passing concentrically through the disc, an arm affixed to the last named shaft, a sleeve rotatable on the last named shaft, an arm affixed to the sleeve, two lapsed time wheels rotatable on the other of the shafts, a shaft journaled within the frame and intermediate the spaced apart shafts, two gears rotatable on the last named shaft, a gear affixed to the first named shaft and in mesh with one of the gears on the intermediate shaft, a gear affixed to the sleeve and in mesh with the other of the gears on the intermediate shaft, the respective lapsed time wheels being in mesh with the respective gears carried by the intermediate shaft.

20 25 30 35 40 45 In testimony whereof we affix our signatures.
